UNITED STATES PATENT OFFICE.

ADOLF HOFFMAN, OF LACKAWANNA, NEW YORK.

SUBMARINE-FENDER.

1,257,002.

Specification of Letters Patent. Patented Feb. 19, 1918.

Application filed December 5, 1917. Serial No. 205,481.

To all whom it may concern:

Be it known that I, ADOLF HOFFMAN, a citizen of Russia, resident of Lackawanna, county of Erie, and State of New York, have invented certain new and useful Improvements in Submarine-Fenders, of which the following is a specification.

This invention relates to improvements in submarine fenders as applied to sea going vessels, and has as its special object the provision of means whereby a torpedo directed against the hull of a vessel may be seized and held so as to avoid injury being done to the ship.

15 A further object is to provide torpedo receiving elements arranged alongside the ship's hull, made of flexible, pliable material so as to avoid detonating a torpedo coming in contact, preventing explosion of the same.

20 These and other like objects are attained by the novel construction and combination of parts hereinafter described and shown in the accompanying drawings, forming a material part of this specification, and in 25 which—

Figure 1 is a side elevational view of a conventional type of ship showing the application of the invention.

Fig. 2 is a top plan view of the same.

30 Fig. 3 is an enlarged fragmental horizontal sectional view taken on line 3—3 of Fig. 1.

Fig. 4 is a fragmental side view showing a modified form of plate construction and 35 receiving elements.

Fig. 5 is a vertical sectional view taken on line 5—5 of Fig. 4.

Fig. 6 is a fragmental sectional view taken on line 6—6 of Fig. 1.

40 Fig. 7 is a side elevational view showing a modified arrangement of contact plate.

Fig. 8 is a top plan view of the same, shown in an extended position, parts being broken away in order to show the construction.

45 Fig. 9 is a similar top plan view of the same, the plate being in a closed or folded position.

Fig. 10 is a vertical sectional view taken 50 on line 10—10 of Fig. 7, and

Fig. 11 is a similar vertical sectional view taken on line 11—11 of Fig. 7.

In the drawings, the ship, indicated by the numeral 10, is of an ordinary type of 55 construction and has rigidly engaged to its hull two horizontal rows of laterally extend-

ing, horizontal bars 14, having nuts 15, rigidly holding plates 16, through which are formed a plurality of uniformly spaced circular openings 17, in which are secured 60 plugs having cylindrical bushings 18, the same being flush or level with the inner sides of the plates.

Extending enlarged cylindrical heads 20, are formed with the bushings, the shoulders 65 19 resting upon the opposite outer sides of the plates, while conical openings 21, suited to receive the front end of a torpedo extend through the plugs, which are made of rubber or other elastic, pliable material and are 70 arranged so that their peripheral edges are juxtaposed, forming a plurality of inclined surfaces receptive of the end of a torpedo which may enter and extend through the openings 22, to the inner side of the plates. 75

As these several plugs are circular in their cross-section, at the triangle formed between any group of three plugs, raised triangular posts 24, are set in the plate, the side and end angles of the posts being shaped in conformity with the beveled interior of the plugs, so as to present a substantially unbroken, continuous surface adapted to receive and divert the point of an incoming torpedo into any of the several openings. 85

In the modification shown in Figs. 4 and 5, the plugs are formed with like bushings 17, fitted to the circular openings formed in the plate, while the heads 30, are rectangular and suited to closely contact one with the other.

The interior beveled surfaces are so arranged as to present substantially no flat space against which the point of a torpedo might strike. 95

These plugs are also made of relatively soft, pliable material into which the points of a torpedo may enter without damage to the vessel or to the torpedo, which may be recovered when its propulsive force is expended, and it will be evident from the foregoing that as the plates containing the plugs extend from a line slightly above the water level to a line below the keel, that any torpedo aimed at the vessel along the 100 side will be received and retained, thereby preventing damage to the vessel's hull. 105

In the modified construction shown in Figs. 7 to 11 inclusive, a plurality of brackets 35 are secured to the hull 10 of the ship, 110 other brackets 36 being arranged at the ends. Extending from the brackets 36 are out-

standing projections 37, corresponding to projections 38 from the brackets 35, which have attached to them arms 40, by means of pivot screws 41, similar screws 42 connecting the arms 43 with the brackets 36. The arms 40 are joined by pivots 44 to studs 45, rigidly secured to the plate 48, similar in all respects to the plate 16, except that the plate 48 may be attached at vulnerable parts of the ship rather than extend over the entire side.

In order that the plate 48 may be brought closely adjacent to the hull 10 of the vessel when desired, hand screws 49, are used to connect the end arms 43 with the plate, the same being normally engaged with projections 50 at one end, and with the innermost opening in a bracket 52 at the other end, in such manner that the arm may be moved from one opening to another as indicated best in Figs. 7 and 8.

At the same time the other arm may be engaged in a post 53, set in the plate 48, thereby holding the plate closely adjacent to the side of the vessel, it being understood that the arrangement of pliable bushings remain as before described, and it is to be noticed that the front edge of the plate 48 is sharply beveled so as to pass readily through the water.

Having thus described my invention, what I claim as new and desire to secure by Letter Patent, is,

1. In a submarine fender, the combination with the hull of a ship, of a plurality of arms rigidly engaged at the side thereof, said arms extending horizontally outward and arranged in two rows respectively near the top and bottom of said hull, a plate rigidly secured at the ends of said arms, said plate containing a plurality of uniformly spaced openings, pliable plugs secured in said openings, the outer surfaces of said plug being closely adjacent one to another, and a conical opening formed in each of said plugs, the bases of said openings being outward.

2. In a submarine fender, the combination with a plurality of rigid arms arranged in two rows at the top and bottom of the ship's hull, said arms extending horizontally outward upon either side thereof, and rigid plates engaged at the outer ends of said arms, of a plurality of uniform openings formed through said plates, pliable bushings secured in the mentioned openings,

enlarged heads formed with said bushings, the periphery of said heads being closely adjacent to one another, conical openings extending entirely through said heads and bushings, the larger end of said conical openings being outward, and means affixed in said plates adapted to direct articles into said openings.

3. In a submarine fender, the combination with a plurality of arms rigidly attached to the hull of a vessel and extending oppositely outward therefrom and rigid plates secured at ends of said arms, of a plurality of openings through said plates, pliable bushings secured in said openings, said bushings being arranged so as to be in intimate contact, and tapering openings formed through said bushings, the larger ends of said openings being disposed outwardly and so formed as to present relatively sharp lines at their junctions.

4. In a submarine fender, the combination with a plurality of arms pivotally attached to the hull of a vessel, extending outward therefrom, and a rigid plate secured at the ends of said arms, of a pair of arms at the ends of said plates, said arms pivotally connected between said plate and the hull of the ship, and means by which said arms may be attached to different points on said plate, so as to hold said plate in an extended position or allow it to be folded alongside the hull of said ship.

5. In a submarine fender, the combination with a plurality of arms pivotally attached to the hull of a ship, and extending outward therefrom, a rigid plate secured at the ends of said arms, a plurality of openings through said plate, pliable bushings secured in said openings, said bushings being so arranged as to be intimately in contact, beveled openings formed in said bushings, the outer edges of said openings presenting sharp lines at their junction at both sides, top and bottom thereof, pivoted arms connecting between the hull of said ship, and the ends of said plate, and means for pivoting said arms to said plate at different positions therealong, so as to permit said plate to be disposed closely adjacent to the hull of the ship, or extended therefrom.

In testimony whereof I have affixed my signature.

ADOLF HOFFMAN.
